UNITED STATES PATENT OFFICE.

CARL AUGUST PETERSEN, OF EVANSTON, ILLINOIS, ASSIGNOR TO THE PURE OIL COMPANY, OF CHICAGO, ILLINOIS, A CORPORATION OF OHIO.

DESIGN FOR A SERVICE-STATION BOOTH.

Application filed October 11, 1928. Serial No. 28,460. Term of patent 14 years.

To all whom it may concern:

Be it known that I, CARL AUGUST PETERSEN, a citizen of the United States, residing at Evanston, in the county of Cook and State of Illinois, have invented a new, original, and ornamental Design for Service-Station Booth, of which the following is a specification, reference being had to the accompanying drawing, forming part thereof.

Figure 1 is a perspective view of a service station booth, showing my new design, Figure 2 is a view in front elevation, and Figure 3 is an end elevation thereof.

I claim:

The ornamental design for a service station booth, as shown.

CARL AUGUST PETERSEN.
